US0D1073673S

(12) **United States Design Patent** (10) **Patent No.:** **US D1,073,673 S**
(45) **Date of Patent:** **** May 6, 2025**

(54) **MONITOR**

- (71) Applicant: **LG ELECTRONICS INC.**, Seoul (KR)
- (72) Inventors: **Heeju Chang**, Seoul (KR); **Yeonjin Kim**, Seoul (KR); **Daihyung Ryu**, Seoul (KR); **Yongsoo Kim**, Seoul (KR); **Daesung Lee**, Seoul (KR)
- (73) Assignee: **LG ELECTRONICS INC.**, Seoul (KR)
- (**) Term: **15 Years**

(21) Appl. No.: **29/908,085**

(22) Filed: **Jan. 11, 2024**

(30) **Foreign Application Priority Data**

- Jul. 18, 2023 (KR) 30-2023-0027705
- (51) **LOC (15) Cl.** **14-02**
(52) **U.S. Cl.** ..... **USPC D14/371**

(57) **CLAIM**

The ornamental design for a monitor as shown and described.

DESCRIPTION

FIG. 1 is a front perspective view of a monitor showing our new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof; and,

FIG. 9 is another front perspective view of the monitor of FIGS. 1–8, showing the display unit of the monitor in a rotated configuration.

The broken lines indicate portions of the article that form no part of the claimed design.

1 Claim, 9 Drawing Sheets
